UNITED STATES PATENT OFFICE.

WILLIAM H. WALDRON, OF NEW BRUNSWICK, NEW JERSEY.

BLOCK-PRINTING MACHINE.

1,251,144.

Specification of Letters Patent. Patented Dec. 25, 1917.

Application filed April 6, 1916. Serial No. 89,497.

To all whom it may concern:

Be it known that I, WILLIAM H. WALDRON, a citizen of the United States, and a resident of New Brunswick, county of Middlesex, State of New Jersey, have invented certain Improvements in Block-Printing Machines, of which the following is a specification.

My invention relates to certain improvements in block printing machines of the type illustrated in the patent granted to me on the sixth day of July, 1915, No. 1,145,821.

My present invention relates to certain improvements in the details of construction of the machine whereby more satisfactory work can be accomplished than with the machine of the above mentioned patent.

One object of my invention is to arrange the mechanism so that access may be had to the parts at each side of the machine.

Another object of the invention is to locate the selector rods so that they will not be injured and will not interfere with the other parts of the apparatus.

25 A still further object of the invention is to provide means whereby each latch for a block carrier is controlled by a cam.

Still another object of the invention is to provide accurate mechanism for reciprocating the main or inking troughs so as to allow them to reciprocate quickly without undue splashing.

These objects I attain in the following manner, reference being had to the accompanying drawings, in which:

Fig. 1^a is a side view of the feed end of a block printing machine;

Fig. 1^b is a side view of the delivery end of a block printing machine illustrating my 40 invention;

Fig. 2 is a transverse sectional view on the line 2—2, Fig. 1^a;

Fig. 3 is a transverse sectional view on the line 3—3, Fig. 1^b;

45 Fig. 4 is a view of the rear end of the machine;

Fig. 5 is a side view illustrating the mechanism shown in Fig. 4 at the rear end of the machine;

50 Fig. 6 is an enlarged view of the paint reservoir reciprocating mechanism on the line 6—6, Fig. 7;

Fig. 7 is a sectional view on the line 7—7, Fig. 6;

55 Figs. 8^a and 8^b are diagrammatic plan

views showing the arrangement of the selecting rods;

Fig. 9 is a detached perspective view showing the action of the latch operating rods;

Fig. 10 is a longitudinal sectional view on the line 10—10, Fig. 4;

Fig. 11 is a sectional view of one of the cam shafts with the cams thereon;

Fig. 11^a is a sectional view on the line 11^a—11^a, Fig. 11;

Fig. 12 is an enlarged sectional elevation through the machine at one of the carriers;

Fig. 13 is a sectional view on the line 13—13, Fig. 14;

Fig. 14 is a sectional view on the line 14—14, Fig. 6;

Fig. 15 is a view illustrating the "Geneva stop" mechanism used in feeding the material through the machine; and

Fig. 16 is a diagrammatic plan view illustrating a rug printed on the machine.

My invention, while it relates particularly to a block printing machine for printing any suitable fabric for any purpose, is especially adapted for use in printing rug designs on a suitably prepared material. The designs, after being printed, are cut into sections to form rugs.

Before beginning the description of the invention in detail, I would have it understood that the material is fed intermittently through the machine by suitable endless bands, in the present instance, which engage the material and move it a given distance intermittently. There is a series of printing blocks mounted on independent vertically reciprocating block carriers which, in the present instance, are actuated by cams and these cams are so formed and the mechanism is so

geared that, when the material is at rest, the block carriers make a vertical reciprocating movement and deposit, on the surface of the material, the pigment in a suitable design.

The printing blocks, when they are moved to the elevated position, are supplied with the pigment by reciprocating reservoirs which pass under the blocks, the roller in the reservoir coming in contact with the printing surface of the blocks.

The above description is that of the ordinary horizontal block printing machine, but, in the ordinary machine, the blocks all have a movement to and from the material after each intermittent movement of the material,

60

100

105

110

and, consequently, only repeats can be printed. One block merely places another color on the same space upon which the previous block placed its color.

5 By my improvements set forth in the above mentioned Letters Patent, I provide means whereby some of the blocks can be automatically held out of action while certain portions of the material are passing 10 thereunder so that the blocks do not make an impression on a particular portion of the material. Therefore, bordered rug designs can be printed on the machine as the blocks having the end border thereon can be held 15 out of action while that portion of the material having the body design thereon is passing under the block.

A machine to accomplish this purpose necessarily takes a great many more blocks 20 or printing units than a machine in which the design is duplicated at each intermittent movement of the material. Therefore, a rug design consisting of several colors requires a large number of printing units and 25 the present machine is adapted for printing large rugs and these rugs may be printed in eight different colors, if desired.

A machine of this type is naturally of 30 great length and preferably of considerable width and as each section, as well as each design, must match, the machine must be accurately made and the parts so designed that the printed design will be substantially continuous and unbroken.

35 My present invention relates to the construction of these parts so that accuracy is assured and quick attachment can be attained.

In Figs. 1^a and 1^b, I have shown two ends 40 of the machine and the first and last printing block carrier as the intervening block carriers are simply duplicates of these. In the present machine there are twenty-four 45 of these carriers and each carrier has its own reciprocating mechanism. There is independent locking mechanism for each carrier so that the carriers can be locked out of action automatically.

Referring to the drawings, 1, 1 are the two 50 longitudinal side frames of the machine having upper beams 2 and lower beams 3. These beams are spaced apart by standards 4. 5 is a central longitudinal frame which is connected to the side frames by lower transverse 55 beams 6 and upper transverse beams 7. The frame thus formed is mounted on flanged wheels 8 adapted to bearings in the transverse beams 6 and travels on rails 9 so that the entire structure can be shifted laterally. 60 The object of this construction is to allow the machine to be moved in front of the different sections of a drying room, as it will be understood that after the sections of fabric have been printed they are immediately conveyed into a compartment in a

drying chamber and when one drying chamber is filled the machine is moved laterally so that it will be moved in line with another drying chamber, and so on, until the entire drying room is filled with material. When 70 the material is dried it is removed from the drying room, starting with the first section, so that the machine can be returned to its original position and the operation repeated.

75 Supported on the upper transverse beams 7 is the platen or table 7^a over which the material travels and which supports the material while it is being printed. This platen is made up of heavy sections directly under 80 the printing block and light connecting sections. Uprights 10 are secured to the side frames and these uprights are spaced a given distance apart and carry overhead rails 11 formed of angle beams and mounted on these 85 rails is the traveling overhead crane 12 having chain drums 13. The chains 14 of these drums are arranged to engage the block carriers or the paint reservoirs when it is desired to remove them from the machine. 90 This crane 12 can be moved either by hand or by power without departing from the essential features of the invention.

I will first describe the printing block carriers. Secured to the upper bar of each 95 side frame of the machine are brackets 15 in which the vertical members 17 of the block carriers 16 are mounted. These vertical members are connected by transverse members 18 which consist of two beams, in 100 the present instance, spaced apart and so designed as to hold the printing blocks 19, which are clamped thereto, as shown clearly in the drawings. The means of securing the blocks to the transverse beams may be 105 modified without departing from the essential features of the invention.

In the present instance, these blocks are about a foot and a half wide and about nine feet long so that a rug nine feet wide can 110 be printed on the machine. The rug may be made of any length desired. The mechanism for intermittently moving the material through the machine is so designed that the movement will be one foot and a half exactly, or a distance equal to the width of the blocks so that, when one block after another makes an impression, the several impressions will accurately match.

115 20 is a longitudinal shaft extending substantially the full length of the machine and 21, 21 are the transverse cam shafts. There is one of these cam shafts for each carrier 16. The cams 22 are mounted on each end of the shaft and each cam bears 125 upon a roller 23 carried by a pin projecting from the vertical members 17 and the cam has an elevated portion 24 which lifts the carrier to its extreme position so that the inking or paint distributing mechanism 130

can be passed under the printing blocks when the carrier is out of action.

25 is a block projecting from each side of the carrier and arranged to engage the blocks are latches 26 mounted on a shaft 27 extending across the machine, see Fig. 3, and on each shaft is an arm 28 having a finger arranged to be engaged by a sleeve 29 secured to a rod 30. There is a series of these rods, in the present instance, one for each printing block carrier, and by arranging the sleeves 29 on the rods any particular rod can actuate any particular arm 28 of a shaft 27. The rods 30 are mounted in bearings 31 arranged at intervals throughout the length of the machine so as to prevent them from sagging.

At one end of each rod 30 is secured a plunger 32 adapted to slide in a bearing 33 secured to the rear end of the machine and a key prevents this plunger from turning in the bearing. The plunger is of greater diameter than the rod and forms a shoulder 34 against which bears an arm 35 of the lever 36, which is pivoted at 37. The lever is forked and extends on each side of the frame as clearly shown in Figs. 9 and 10. The levers are arranged side by side, as shown in Fig. 4, and the rod 37 is mounted 38 in bearings in the side frames of the machine. 38 is a cam shaft detachably mounted in bearings 39 on brackets 40 secured to the side frames of the machine, see Figs. 4 and 5. The caps of the bearings are pivoted 35 and secured by swivel bolts so that they can be swung clear of the cam shaft to allow it to be bodily placed in the bearings or removed therefrom.

The cam shaft 38 is made as clearly shown 40 in Fig. 11, being arranged so that it will be bodily removed from its bearings in the machine, as it will be understood that there is a series of these shafts having cams thereon for rugs of different sizes and for rugs differing in the number of colors. Each cam shaft is enlarged, as at 38^a, and is preferably made tubular, as shown. The cams 41 are in the form of rings with hubs 41^a thereon and are mounted on the enlarged portion of 50 the shaft and are secured thereto by a key in the present instance. The end cams have set screws which retain the cams longitudinally on the shaft. Near each end of the shaft 38 is a collar 38^b which rests against the inner side of the bearing and holds the shaft in the proper alinement with the levers which they actuate.

By the above construction, the time necessary to change the machine to print rugs 60 of different sizes is materially reduced. On the shaft 38 are twenty-four cams 41, in the present instance, and there are also twenty-four levers 36 and twenty-four rods, but it will be understood that the number of 65 cams and of levers and rods is the same.

In this machine twenty-four cams are used as there are twenty-four printing block carriers. In other machines, however, there may be a fewer number of cams, or a greater number.

At the end of each rod opposite from the levers are springs 42 which tend to hold the plungers 32 against the arms 35 of the levers and to hold the latches 26 in engagement with the block 25. The cams release the 75 latches which fall by their own weight clear of the blocks, but the moment the high points of the cams pass the lever 36 the springs 42 force the latches 26 forward so that when the block, in its upward movement, passes the end of the latch it is projected under the block so that as the carrier again descends it will be stopped by the latch and will be held clear of the inking mechanism and the surface to be printed.

In the present instance, each of the levers 36 has a friction roller 43 which bears against its particular cam. The bearings 39 for the cam shaft 38 are adjustably mounted on the bracket 40 so as to be moved to and from the levers 36. In the present instance, mounted in each bearing is a screw shaft 44 having a beveled pinion 45 at its outer end which meshes with a beveled pinion 46 on a shaft 47 provided with a handle 48 by which it can be turned so that, on turning the handle, the bearings can be moved to and from the friction rollers 43 of the lever 35. On the end of the cam shaft 38 is a gear wheel 49 which meshes with an intermediate gear 50 carried by a segment 51 and is driven by a pinion 52 on a shaft 53. The segment 51 has a series of holes to which is adapted a pin 54 so that when the shaft 39, with gears of different diameters, is placed in the machine, the segment 51 can be shifted so as to allow its gear wheel 50 to mesh with the gear wheel 49. The shaft 53 has a sprocket wheel 55 around which passes a drive chain 56 from a sprocket wheel 57 on the shaft 58 110 which drives the feeding mechanism for the fabric.

The diameter of the wheel 49 is proportionate to the length of the rug to be printed and is changed for each length. The pinion 52 is rotated one full revolution at each intermittent movement of the material and this movement is 18 inches in the present instance, and the pinion 52 is so proportioned. The gear wheel 49 is a multiple of 120 this and equals the length of one rug so that each cam with a single "high" spot will actuate its catch once in each length of rug.

In printing some types of rugs, each cam may have two "high" spots so as to operate 125 the catch twice in each revolution and in this case the gear wheel will have to be proportioned accordingly.

It will be seen by the above description that instead of having a single shaft upon 130

which the cams can be adjusted for rugs of every size, or rugs differing in the number of colors, I provide a shaft for each change and each shaft has its own cams previously located thereon so that all that is necessary is to open the bearings, remove the cam shaft that is in the machine, and to substitute another cam shaft which will correspond to the type of rug to be printed. This not only saves considerable time in changing the machine, but also prevents mistakes due to careless adjustment of the cams on the cam shafts by workmen who are not skilled in the art, as it will be understood that in machines of this type, particularly the very large machines, such as the one under consideration, any mistake in timing would be fatal to the proper printing of the fabric.

By making the bearings 39 adjustable toward and from the lever 35, I am enabled to more readily place the cam shaft in position than if the bearings were located in a fixed position, as the pressure of the springs 42 on the rods 30 would prevent the ready location of the cam shaft in position. By adjustably mounting the bearings they can be moved away from the rollers 43 on the levers so that the entire cam shaft can be taken out and another readily placed in position. Then by again adjusting the bearings, the cam shaft will be in proper position with respect to the levers.

In the present instance, the shaft 20 extends substantially the full length of the machine and has a series of worms 59 which mesh with worm wheels 60 on the transverse cam shafts 21, Fig. 3. These worm wheels are located in casings 61 secured to the bearings 62 of said shafts. The worms are mounted in bearings 63 secured to the center frame 5, as shown in Fig. 3, and the worm shaft is driven from an electric motor 64, in the present instance, mounted on the frame 6, and through intermediate shafts 63 and 66 and the gearing shown by dotted lines, Fig. 2. Other means for driving the worm shaft may be resorted to without departing from the essential features of the invention.

Each carrier 16 is balanced by counterweights 67 which are attached to chains 68 passing over sprocket wheels 69 and are attached to the inner side of each vertical member 17 of the block carriers. The transverse members 18 of the block carriers are secured to the vertical members 17 by bolts 70, as shown in Fig. 2, so that, when the chains 14 of the crane are attached to the transverse member 18 of the block carrier, the bolts 70 can be removed and the entire horizontal section, with the blocks thereon, can be removed from the machine.

It will be noticed, on referring to the drawings, that the blocks 19 are secured to transverse members 19^a, and clamp plates

17^a are secured to these members by bolts 72 and overlap the lower flange of the I-beams which form part of the transverse member 18 of the carrier. The blocks can be adjusted laterally in respect to the transverse members 18 by set screws, as clearly shown in Fig. 1^b, and the blocks can be brought into proper alignment by placing making-up strips between the clamps and the blocks so as to insure a perfect impression. 75

I will now describe the mechanism for intermittently moving the material forward in the machine. Referring to Figs. 1^a and 1^b, 74, 74 are endless metallic bands, one at each side of the machine. Each band passes 80 around sprocket wheels 76 on transverse shafts 77 and has pins 75 located at intervals to engage the material to hold it in proper position while it is moving through the machine. The bands are preferably 85 made of thin flexible steel and the upper run of each band travels on tracks 78, which also extend the full length of the machine. The lower run is supported at intervals by guides 92 hung from the upper beams 2 of the side 90 frames by rods 93.

The shaft 77 at the rear end of the machine has a gear wheel 79 thereon which meshes with a gear wheel 80 on a shaft 81 to which is secured a star wheel 82, Fig. 15. This 95 star wheel is driven from the shaft 58 by a wiper 83 thereon having projecting pins 83^a which enter the radial slots in the star wheel, the body of the wiper conforming to the shape of the star wheel between the slots 100 so as to lock it in position during the interval of time between its movement by the pins. This is the common method of intermittently driving the elements and is known as the "Geneva stop." 105

The shaft 58 is driven from the shaft 84 through gearing shown by dotted lines in Fig. 1^b and this transverse shaft 84 is driven from the longitudinal shaft 20 through the worm 59^a and a companion worm wheel on 110 said shaft 84. On the shaft 84, in the present instance, is a belt wheel 85 around which passes a belt, shown by dotted lines in Fig. 1^b, to a wheel 86 on a shaft 87 adapted to bearings on a bracket 88. On this shaft are 115 upper slitters 89 which act in conjunction with the lower slitters 90 on a shaft 91 mounted on the frame of the machine so that as the material is fed through the machine and after it has been printed, in the present 120 instance, the edges are trimmed by the slitters. This mechanism may be omitted where the material is trimmed on a separate machine.

The mechanism for supplying the pigment 125 to the printing blocks is operated as follows: 94, 94 are carriages mounted on rollers 95 adapted to brackets 96 on the upper beams 2 of the side frames 1. In the present instance, there is a longitudinal rack 97 and on the 130

axles of the wheels 95 are pinions 98 which mesh with the racks, as clearly shown in Figs. 6 and 7. Carried by a segment 99 is an intermediate pinion 100 which meshes with a gear wheel 101 on the shaft 102 of the color roll 103 which is located in the reservoir 104 and at each side of this roll are doctors 105 which can be adjusted to remove a certain quantity of color from the roll so as to insure the delivery of the proper amount of color to the printing blocks. There is one of these inking carriages for each printing block carrier so that in a machine having twenty-four printing block carriers there are also twenty-four inking reservoirs and they move from one side to the other of the printing blocks, and, as they travel under the blocks, they supply pigment to the projecting surfaces of the blocks. It is essential, particularly in machine of large size, that the reciprocating movement shall be as even as possible, otherwise there will be a tendency to splash and also a tendency to deposit a greater amount of pigment on that portion of the block which is in contact with the roller when the inking mechanism is subjected to a jarring action.

By the mechanism which I will now proceed to describe, I have provided means whereby the movement of these several inking carriages is produced without jar so as to insure an even application of the pigment to the printing surfaces. The several carriages are connected by links 106 and each end carriage is connected by long links 107 to the operating arms 108 pivoted at 109 to the side frames at each side of the machine, as clearly illustrated in Figs. 1^a and 1^b and in Fig. 6. The mechanism for operating the arms 108 is duplicated at each end of the machine and the above described mechanism is clearly shown in said figures.

110 is a shaft which extends from one side of the machine to the other and is adapted to suitable bearings. On this shaft, at each side of the machine, is a rocker 111 and each rocker is connected by a link 112 to an arm 108. The rocker is slotted at 113 and 113^a and on each side of the shaft 110 and running parallel therewith are shafts 114 and 115, each having a disk 116 and each provided with a pin 117, the pin of one disk being adapted to enter the slot 113 and the pin of the other disk being arranged to enter the slot 113^a as the shafts revolve. The pins are so set that one will follow the other, thus giving a rocking motion to the rocker 111 and imparting a reciprocating motion to the inking carriage. The shaft 114 at the forward end of the machine is driven from a shaft 118 through gear wheels 119 and 120 and the shaft 118 is driven through a worm 59^b and worm wheel 60^c from the longitudinal shaft 20. While the shaft 114 at the rear end of the machine is

driven from the last cam shaft 21, Fig. 1^b, through gearing 119^a and 120^a, in order to drive each shaft 115 in proper time with the shaft 114, I provide a train of gears 121, 122, 123 and 124, connecting each shaft 115, 70 with its companion shaft 114 so that each shaft moves in proper time and will actuate the rocker 111 at one end of the machine in proper time with the rocker 111 at the opposite end of the machine. 75

On each shaft 110 is a detent which holds the rocker shaft at the limit of its movement in either direction. This detent consists of a disk 125, which is cut away at each side, as at 126, forming shoulders 127 against 80 which are bolted plates 128 which are secured to the shoulders by bolts, as clearly shown in Fig. 13. Each plate is beveled to form a V-groove and on a lever 129 pivoted at 130 is a V-shaped blade 131 adapted to enter the groove formed by the plates 128 and to hold the shaft 110 in position. This blade 131 is held by a transverse bolt and can be adjusted by a screw 132. On the opposite end of the lever 129 is a friction roller 133, 90 which is acted upon by a cam 134 on the shaft 114 so that, when the high portion of the cam is in contact with the roller 133, it holds the blade 131 in the V-groove, but when this high portion is passed, the disk 95 125 and its shaft 110 are released so that the rocker 111 can move to the opposite position, where it is again held by the blade which enters the groove at the opposite side of the disk. The detent holds the rockers 100 when the pins are out of the slots and prevents accidental movement of the pigment distributor. I preferably provide an air cylinder 142 at each end of the machine, which is pivoted at 143 to the side frame 105 of the machine, and I locate a piston in this cylinder, the rod 144 of which is connected to the levers 108. There is a certain amount of leakage in the piston and the air in the cylinder will form a cushion for the levers 110 controlling the movement of the pigment distributors. As the pigment distributors are connected together by links and are connected at one end to a lever and at the opposite end to a lever, each of which is under positive control, the distributors will be moved into and out of inking position without jar, since all of the links are under tension, consequently, uneven distribution of the pigment upon the surface of the printing 115 blocks is avoided.

The roll of material to be printed is placed on a mandrel 135, Fig. 1^a, at the forward end of the machine. This mandrel is adapted to a slot in the pivoted bearing 136 125 and secured therein by pins 137. This bearing is then swung on its pivot until the mandrel 135 drops into the opposite bearing 138 on a bracket forming part of the machine. The fabric passes over a roller 139 and is 130

engaged by the pins 75 on the bands 74, which convey it intermittently through the machine.

I have described the present machine as having twenty-four reciprocating printing block carriers and there are twenty-four cams and twenty-four rods shown. There is a latch for each carrier and only one carrier is controlled by a cam and its rod. This arrangement is possible, owing to the location of the rods between the side frames of the machine and by this arrangement the shape of said cam is simplified.

I have not described the power mechanism for shifting the entire machine laterally so as to bring it in line with any one of a series of drying compartments, as this may be accomplished in many different ways.

20 It will be seen that by the use of a machine constructed as described I am enabled to print rug designs having borders at the ends and at the sides, or other designs can be printed in which the design is not repeated at every block width. Consequently, a machine of this type can print more elaborate designs than those in which the blocks are not controlled. Furthermore, the machine is so constructed that several sections 25 making up the entire design will exactly match.

In printing material with rug designs for instance, I supply the reservoirs with the pigments desired, then, if a rug six feet long 30 is to be printed, such as is illustrated in Fig. 16, it will take three sets of blocks for each color, if there is the same number of colors in the border as in the body of the rug. The cam shaft, having the number of cams 35 properly located for a six foot rug, is placed in the machine and the sleeve 29 on the rods 30 can actuate any particular arm 28. If it be desired to cut out some of the block carriers, then the carriers are locked in the 40 raised position by the hand locks 140. The material is then placed on the mandrel 135 and the mandrel is located in its bearing 138, the material being preferably connected to the end of the material previously printed 45 in the machine, or to the waste material that is used to try out the machine before printing the final design. The machine is then set in motion and the material is fed intermittently through the machine, the intermittent movement being equal to the width 50 of the printing blocks, and, as it passes under certain of the blocks, they are automatically released and are allowed to make an impression after being properly supplied 55 with the pigment. The inking reservoirs are reciprocated under the several blocks, but only those that are printing are provided with pigment, the others being held clear of the roller by their latches so as to

prevent an over supply of pigment being deposited on certain blocks.

If, for instance, a block prints a right hand bordered design on the material, this particular block will be held out of action by the selecting cams until these sections of the material have passed the block, but when the fourth section is under the block, the block will be released and the impression will be made and this impression will match exactly with the impression of another block which has printed another color on the same section. The same process is carried out when the design for the opposite end of the rug is printed, but when the design for the center of the rug is printed, then two impressions may be made, one following the other, as these impressions are similar in design and make up the body of the rug. If the rug is of greater length than six feet, then the number of body impressions is increased without increasing the number of end impressions. When the rug is finished the several sections are so matched that the joints are not discernible.

While I have described my invention as particularly adapted for printing bordered rugs, it will be understood that the invention can be used for printing running designs where the design of one section differs from that of an adjoining section. In fact, a machine built in accordance with my invention will be able to print a design which will not be duplicated except at long intervals, thus materially increasing the value of the product.

Further, by my invention I am enabled to print certain colors on given portions of the material. In fact, the mechanism is so controlled that the most elaborate designs can be printed on the material at a comparatively low cost.

While my invention is particularly adapted for printing floor coverings known as "oilcloth" and like material, it can be used for printing certain classes of carpet fabrics, curtains, and certain grades of paper for wall coverings without departing from the spirit of the invention.

I claim:

1. The combination in a block printing machine of the horizontal type, of side frames; a platen located between the side frames; means for conveying material intermittently over the platen; a series of longitudinal rods placed side by side and located under the platen; means for guiding said rods; a series of transverse shafts having arms, said arms being out of line; means on each rod for engaging an arm; a plunger at one end of each arm forming a shoulder; a series of two-armed levers, one arm of each lever being arranged to bear upon the shoulder of a rod; a cam shaft; a series of cams

thereon arranged to come in contact with the other arms of said levers so as to move the rods in one direction; and a spring on each rod for moving the rods in the opposite direction.

2. The combination in a block printing machine of the horizontal type, of a side frame; a platen located between the side frames; rails at each side of the platen; an

endless band adapted to travel on each rail; means for intermittently moving the bands; a series of printing block carriers; means for vertically reciprocating the printing block carriers; a series of longitudinal rods

arranged side by side under the platen; a transverse shaft at one end of the machine; a series of two-armed levers mounted on the said shaft, one arm of each lever engaging a rod; a detachable transverse cam shaft, also at one end of the machine, and having a series of cams thereon arranged to come in contact with the other arm of each lever; and means for turning the cam shaft to impart a longitudinal movement to the rods.

3. The combination in a block printing machine of the horizontal type, of a frame; means for moving material to be printed over the frame; a series of block carriers; printing blocks thereon; means for actuating the block carriers; a transverse shaft at one end of the machine; bearings for the cam shaft; means for detachably securing the caps of the bearings in position so that the cam shaft can be bodily removed from the bearings; a series of cams on said shaft; means for holding certain of the blocks out of action, said means being controlled by cams; and means for driving the cam shaft.

4. The combination in a block printing machine of the horizontal type, of a frame; means for intermittently moving the material to be printed through the machine; a series of intermittently operated block carriers; printing blocks thereon; a transverse shaft at each block carrier; latches on each shaft engaging the carrier to hold it out of action; a series of longitudinal rods for actuating the transverse latch shafts; a series of levers engaging the said rods; a cam shaft having cams thereon for actuating the levers; sliding bearings for the cam shaft; a support for the bearings; and means for moving the said bearings to and from the levers.

5. The combination in a block printing machine of the horizontal type, of a frame; means for intermittently moving the material to be printed through the machine; a series of block carriers; printing blocks thereon; latch mechanism for holding certain of the blocks out of action; a series of rods for actuating the latches; a series of levers for independently moving the rods longitudinally; a cam shaft having a series

of cams thereon for actuating the levers; 65 adjustable bearings for the cam shafts; means for moving the bearings in unison; a gear wheel on the cam shaft; a segment; an intermediate gear wheel thereon; a driving shaft; a pinion on the said driving shaft 70 meshing with the intermediate wheel; and means for adjustably holding the segment in position.

6. The combination in a block printing machine of the horizontal type, of a series 75 of block carriers; means for vertically reciprocating the carriers; means for intermittently feeding the material through the machine; a series of connected pigment distributors; and operating means connected at each end of the series for reciprocating the pigment distributors under the printing blocks.

7. The combination in a block printing machine of the horizontal type, of a series 85 of block carriers; means for vertically reciprocating the carriers; means for intermittently feeding the material through the machine; a series of connected pigment distributors, a lever at each end of the machine; and means, at each end of the machine, for moving each lever so that the pigment distributors will be under the control of the mechanism for moving them in both directions.

8. The combination in a block printing machine of the horizontal type, of a series 95 of block carriers; means for vertically reciprocating the carriers; means for intermittently feeding the material through the machine; a series of connected pigment distributors; a lever connected at each end of 100 the series; a slotted rocker connected to the lever; two operating shafts geared together and having arms provided with pins arranged to enter the slots in the rocker; and means for driving the said shafts.

9. The combination in a block printing machine, of a series of vertically reciprocating block carriers; printing blocks thereon; means for actuating said carriers; means for intermittently moving material through the 110 machine; a pigment distributor for each printing block; links connecting the several distributors so that they will travel in unison; a slotted rocker at each end of the machine connected to the enchainable distributors; two driven shafts at each end of the machine, one at each side of the rocker; and having pins arranged to engage the rocker, said pins being so set that when one pin is in engagement the other pin is out of engagement, whereby the rocker is reciprocated first in one direction and then in the opposite direction.

10. The combination in a block printing machine of the horizontal type, of a frame; 125 a series of intermittently reciprocating printing block carriers; means for actuating said carriers; means for intermittently moving

- material through the machine; a series of pigment distributors arranged to reciprocate under the block carriers when they are in the raised position and to supply pigment thereto; links connecting the several pigment distributors; a pivoted lever at each end and at each side of the machine; a link connecting each lever with the series of pigment distributors; a transverse shaft at each end of the machine; a slotted rocker on each end of the shaft; a link connecting the rockers with one of the levers; two transverse shafts; one on each side of the rocker, each shaft having an arm at each end and a pin on the arm arranged to enter the slots in the rocker so that as the said shafts rotate the rocker will be rocked and a reciprocating motion will be given to the pigment distributors. 13. The combination in a block printing machine of the horizontal type, of a series of carriers; printing blocks thereon; means for vertically reciprocating the carriers; means for feeding the material intermittently through the machine; a pigment distributor for each printing block, said distributors being connected together; means at each end of the machine connected to the pigment distributors and working in unison; and a detent for retaining the said mechanism while the distributors are at rest. 70
14. The combination in a block printing machine of the horizontal type, of means for intermittently moving the material to be printed through the machine; a series of printing block carriers spaced a given distance apart; blocks thereon arranged to make an impression on the surface of the material as it passes through the machine; a series of pigment distributors connected together and arranged to reciprocate under the printing blocks; a lever connected to the pigment distributors; a slotted rocker connected to the lever; two shafts having arms with pins thereon arranged to enter slots in the rocker; means for driving the shafts in unison; a cam on one of said shafts; a detent lever actuated by the cam; and a disk on the rocker shaft arranged to be engaged by the lever when in either of its two extreme positions. 80
15. The combination in a block printing machine, of a reciprocating pigment distributor; a rocker connected to the pigment distributor; two shafts having pins arranged to engage the rocker; a disk secured to the rocker shaft; two sets of plates thereon spaced a given distance apart; the plates of each set being beveled to form a V-groove; a pivoted lever having a V-shaped blade at one end arranged to enter either of the grooves; and means for adjusting the blade; and a cam on one of said driving shafts arranged to actuate the lever so that the lever will enter the V-groove when the rocker is at the two extremes of its movement. 90
16. The combination in a block printing machine of the horizontal type, of two longitudinal side frames; and a central longitudinal frame; cross beams connecting the central frame with the side frames; guides in the side frames; a series of block carriers adapted to the guides; printing blocks on the carriers; a series of transverse shafts having cams thereon for raising the block carriers; a longitudinal rail at each side of the machine; pigment distributors arranged to travel on the rails; means for intermittently reciprocating said carriers; two endless bands having pins thereon arranged to convey material to be printed intermittently through the machine; wheels at each end of the machine around which the bands pass; rails for supporting the upper run of 110
11. The combination in a block printing machine of the horizontal type, of a frame; a series of intermittently reciprocating printing block carriers; means for actuating said carriers; means for intermittently moving material through the machine; a series of pigment distributors arranged to reciprocate under the block carriers when they are in the raised position and to supply pigment thereto; links connecting the several pigment distributors; a pivoted lever at each end and at each side of the machine; a link connecting each lever with the series of pigment distributors; a transverse shaft at each end of the machine; a slotted rocker on each end of the shaft; a link connecting each rocker with one of the levers; two transverse shafts, one on each side of the rocker, each shaft having an arm at each end and a pin on the arm arranged to enter the slots in the rocker so that as the said shafts rotate the rocker will be rocked and a reciprocating motion will be given to the pigment distributors; a train of gearing connecting the two shafts which actuate the rocker; and means for driving one of said shafts, the parts being so connected that the two shafts will be driven in unison. 12. The combination in a block printing machine, of a series of vertically reciprocating block carriers; means for actuating said carriers; means for intermittently moving material through the machine; a pigment distributor for each printing block mounted on the carriers; links connecting the several pigment distributors so that they will travel in unison; a slotted rocker at each end of the machine connected to the enchain pigment distributor; two driven shafts at each end of the machine, one at each side of the rocker and having pins arranged to engage the rocker, said pins being so set that when one pin is in engagement the other pin is out of engagement, whereby the rocker is reciprocated first in one direction and then in the opposite direction. 130

each band; a platen located between the bands; a longitudinal driving shaft adapted to bearings carried by the central longitudinal frame; a series of worms on said shaft; a series of worm wheels on the transverse cam shafts for actuating the carriers; a motor carried by the frame of the machine and geared to the longitudinal driving shaft; and wheels for supporting the frame so that the entire structure can be moved laterally.

17. The combination in a block printing machine, of a frame having printing block carriers thereon; means for engaging and

holding the carriers out of action; selector rods; cams for actuating said rods; a shaft upon which the cams are located, said shaft having an enlarged portion, the cams being in the form of rings with hubs thereon whereby they can be located on the enlarged portion of the shaft and held thereto, the shaft having collars; and bearings in which the shaft is detachably mounted, the collars resting against the bearings so as to hold the shaft and the cams in the proper alignment.

WILLIAM H. WALDRON.
